UNITED STATES PATENT OFFICE.

JAMES SCOTT HAINLINE, OF MACOMB, ILLINOIS.

VAULT.

Application filed March 21, 1924. Serial No. 700,869.

To all whom it may concern:

Be it known that I, JAMES SCOTT HAINLINE, a citizen of the United States, residing at Macomb, in the county of McDonough and State of Illinois, have invented a new and useful Vault, of which the following is a specification.

The device forming the subject matter of this application is a vault, adapted to contain a coffin, and the invention aims to provide a device of the kind specified which may be made cheaply out of cypress or some other enduring wood, the construction being such that the gases generated by the decomposition of the corpse will tend to hold the water back, out of the vault. The invention aims, further, to provide novel means for holding together the constituent parts of the body of the vault.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described, it being understood that, within the scope of what is claimed, changes in the precise embodiment of the invention are shown, can be made, without departing from the spirit of the invention.

In the accompanying drawings:—

Figure 1 shows in longitudinal section, a device constructed in accordance with the invention; Figure 2 has a transverse section; Figure 3 is a fragmental longitudinal section; Figure 4 is a fragmental transverse section.

The vault forming the subject matter of this application comprises a base 1 and a body 2 resting on the base. The base 1 preferably comprises any desired number of boards or sills 3 extended transversely of the vault and connected by tongue and groove joints 4. The joints 4 may be cemented, and it will be understood that cement may be used at any point desired in the joints of the device. On the base 1 is fixed a rack 5 made up on longitudinal sills 6 and cross-bars 7 resting on and secured to the sills 6. The rack 5 serves to elevate the

coffin enough so that the corpse will not lie in water, should any water find its way into the vault, although as hereinafter described, the device is so constructed that there is small likelihood of water finding its way into the vault.

The body 2 of the vault comprises end pieces 8 provided adjacent to their inner surfaces with ribs 9 extended along the upper edges of the end pieces, and downwardly along the vertical edges of the end pieces. The ribs 9 are in received grooves 10 formed in the top 11 of the body 2 and in the sides 12 of the body 2. The top 11 and the sides 12 of the body 2 of the vault are made up of slats 14, which are tongue and grooved together, as shown at 15. The top 11 and the sides 12 are held on the ends 8 by securing elements 16, such as screws, the same being located outwardly of the ribs 9 and the grooves 10, as shown in Figure 3. The lowermost slats of the sides 12 are provided with recesses 17, and through the remaining slats of the sides 12 and the top 11 extend bores 18. Transverse ties 19 are mounted in the bores 18 and extend into the recesses 17. Nuts 20 are threaded on the ties 19 and engage the lowermost slats 14, within the recesses 17, as shown in Figure 4. The nuts 20 are enclosed within cement 21, located in the recesses 17, and cement may be disposed in the bores 18 about the ties or rods 19, as shown at 22. The recesses 17 may be closed by means of plugs 23. The general construction of the body 2 is such that it will be hermetic and air tight. Certain of the boards 3 of the base 1 may be provided with transverse outwardly and downwardly slanting grooves 24, extended beneath the sides of the vault, as shown best in Figure 4.

In practical operations, any liquid exuding from the corpse will find its way out of the vault through the grooves 24. The gases resulting from the decomposition of the corpse will accumulate in the air tight body 2 and prevent the water from entering the vault to any appreciable extent, the rack 5 serving to hold up the coffin to such an extent that any water which may happen to find its way into the vault will be prevented from wetting the corpse.

The device preferably is made of cypress or some other enduring wood, and although

cheaply constructed, will aid in preventing a corpse from being subjected to anything other than the ordinary process of decay.

Having thus described the invention, 5 what is claimed is:—

A vault of the class described, comprising a base, an inverted box-like body resting on the base, and a coffin-rack supported on the

base within the body, the base being provided in its upper surface with a drainage 10 groove extended outwardly beneath the lower edge of the body.

In testimony that I claim the foregoing as my own, I have hereto affixed my signature.

JAMES SCOTT HAINLINE.
